TURBO-MOLECULAR VACUUM PUMP

Henri Louis Garnier, Courbevoie, and Léonide Rabet and Raymond Hippolyte Firmin Marchal, Paris, France, assignors to Societe Nationale d'Etude et de Construction de Moteurs d'Aviation, Paris, France, a company of France

Filed Apr. 20, 1962, Ser. No. 189,021

Claims priority, application France May 15, 1961

1 Claim. (Cl. 230—122)

The present invention derives from the principle of the turbo-compressor rotating at a high speed, such as is currently used in aircraft. Experiments, which agree in every way with the theory, have established that a distinctly higher compression rate is obtained when the turbo-compressor operates in a rarefied atmosphere.

The present invention utilises this knowledge in the field of high vacuums.

In a vacuum pump, the cross-section of the blades is greatly simplified as compared with the cross-section of the blades normally used in turbo-compressors. In fact, the problems connected with flows in the viscous and turbulent conditions are no longer encountered in the case of gases in a molecular condition. The various stages of the vacuum pump are simply constituted by a series of thin discs which are alternately fixed and mobile and on the periphery of which the blades are arranged.

The present invention relates to a turbo-molecular vacuum pump characterised in that the blades have a triangular cross-section and comprise a sharp edge directed towards the chamber to be evacuated, whilst the opposite face to this edge is directed towards the discharge side. In other words, each blade is in the form of truncated prism having a triangular base whose most acute dihedral angle is directed towards the upstream side, i.e. in the direction of the high vacuum. Consequently, the face which is opposite this dihedral angle and whose plane is perpendicular to the axis of rotation of the pump, is turned in the direction of the preliminary vacuum.

This arrangement enables the gases diffused from the chamber to be evacuated to penetrate easily into the ducts which are bounded by the blades and which are wide open to these gases.

The following description with reference to the accompanying drawings, which are given by way of non-limitative example, will make it easy to understand how the invention can be carried into effect, the features brought out either from the text or from the drawings being understood to form part of the said invention.

FIG. 1 is an axial sectional view of a turbo-molecular vacuum pump.

FIG. 2 is a cross-section on II—II of FIG. 1.

FIG. 3 is a partial developed view of two successive blade systems, showing the basic feature of the present invention.

The pump shown in FIG. 1 is of a well-known and already old type, having been proposed by Holweck as early as 1922. Suction is effected through the inlet E, in the median plane of the casing C of the pump, the various stages being arranged symmetrically with respect to the median plane, and the outlets S at the two ends of the casing being connected by a pipe T to the suction P of a forepump (not shown) which may be an ordinary vacuum pump. The shaft A of the turbo-molecular pump can be driven by a built-in motor. This shaft is fast with rotary discs R separated by fixed discs F, on the periphery of which discs the blades are arranged.

According to the present invention, and as FIG. 3 shows clearly, these blades have a triangular cross-sec-

2

tion having a sharp edge *a* pointing in the direction of the suction side (the direction of flow is designated by the arrow *f*, whilst the arrow *r* designates the direction of rotation of the mobile blade system R), so that the ducts delimited by the two neighbouring blades of one and the same disc are wide open to the molecules which are displaced in the direction *f* and do not encounter, in their travel from the upstream to the downstream sides any arresting transverse surface at any time and whatever 10 the angular position of the rotor.

Indeed, the transverse surfaces *s* which form the base of the triangles are directed downstream and consequently are impinged against only by the retro-diffusing molecules, which is also advantageous since it must be taken into account that retro-diffusion of gases always 15 takes place whenever there are zones of different molecular density, this retro-diffusion being effected from the zone of higher molecular density to the zone of lower molecular density.

Furthermore, in order to promote the carrying of the molecules towards the downstream blades, it is convenient to incline the axis of the ducts of one and the same fixed or mobile disc in the desired direction in accordance with the direction of rotation of the pump.

In fact, the form and arrangement of the blades thus formed on the periphery of the discs enable the retro-diffusing molecules to be frequently made to strike against the lateral walls of the ducts and also the transverse faces *s* and to be re-despatched, after temporary absorption, with a component of speed which tends to send them in the downstream direction.

In this way, retro-diffusion is reduced and the output and the compression rate of the pump are increased.

The clearances between the fixed blades and the mobile blades should remain small in order that the gases should 35 be always in the molecular condition.

What is claimed is:

A rotary molecular high-vacuum pump of the kind designed to operate in series with and upstream of an ordinary vacuum backing pump, comprising a succession of alternately rotary and stationary blade rings, the blades of each of said rings having a cross-section in the form of an obtuse angle triangle with a sharp rectilinear front edge and a planar transverse rear face in a plane substantially perpendicular to the rotation axis, the sharp edges of the blades being circumferentially shifted relative to the corresponding planar faces in the direction of rotation in the case of a rotary blade ring and in the opposite direction in the case of a stationary blade ring, successive 45 rotary and stationary blade rings being mutually arranged so that the sharp edges of one blade ring are immediately adjacent the planar faces of the next preceding blade ring.
